UNITED STATES PATENT OFFICE

151,974

DESIGN FOR A BUMPER ENGAGING MEMBER FOR AN AUTOMOBILE JACK

Ralph Gambardella, Warwick, R. I., assignor to
Narragansett Machine Company, a corporation
of Rhode Island

Application October 23, 1946, Serial No. 134,180

Term of patent 3½ years

(Cl. D41—1)

To all whom it may concern:

Be it known that I, Ralph Gambardella, a citizen of the United States of America, residing at Warwick, county of Kent, State of Rhode Island, have invented a new, original, and ornamental Design for a Bumper Engaging Member for an Automobile Jack, of which the following is a specification, reference being had to the accompanying drawing, forming a part thereof.

Fig. 1 is a side elevational view of a bumper engaging member for an automobile jack, showing my new design in the position it assumes on a jack cylinder;

Fig. 2 is a top plan view thereof; and

Fig. 3 is a perspective view thereof with the clamp bolt omitted for convenience of illustration.

The dominant features of the design reside in the portions shown in full lines.

I claim:

The ornamental design for a bumper engaging member for an automobile jack, substantially as shown and described.

RALPH GAMBARDELLA.
